UNITED STATES PATENT OFFICE.

WALLACE ORLANDO WITHAM, OF SALEM, OREGON.

CHICKEN-BROODER.

1,022,218.

Specification of Letters Patent.

Patented Apr. 2, 1912.

Application filed January 5, 1911. Serial No. 600,918.

To all whom it may concern:

Be it known that I, WALLACE O. WITHAM, a citizen of the United States, and a resident of Salem, in the county of Marion and 5 State of Oregon, have invented a new and Improved Chicken-Brooder, of which the following is a full, clear, and exact description.

My invention relates to chicken brooders, 10 and it has for its object to provide one having a heater, curved in cross section, which permits the chickens to get their backs up against the cloth-covered heater, so that their bodies may be warmed in the natural 15 way.

Another object of the invention is to provide means for warming the heater, which will use to the best advantage the heat supplied by a lamp.

20 Still other objects of the invention will appear in the following complete specification, in which the preferred form of my invention is disclosed.

In the drawings similar characters of reference denote corresponding parts in all the 25 views, in which—

Figure 1 is a perspective view showing my invention; Fig. 2 is a transverse sectional elevation of the brooder; and Fig. 3 is a sectional plan view of the heater.

By referring to the drawings it will be seen that a housing member 5 is provided, having sides 6, an inclined end 7, and a rear wall 8, having an opening 9. A compartment 10 is 35 partitioned off in the housing member 5 by members 11 and 12, and in this compartment 10 there is disposed a lamp 13, which is introduced through the opening 9 in the rear wall 8. There is an opening 14 in the 40 top or floor 15 of the housing member 5, and on this top portion or floor 15, there are guide strips 16. On the housing member 5 there is disposed an upper housing member 17, the side walls 18 of which are disposed 45 against the outer sides of the guide strips 16. By this means the upper housing member 17 is held in position. In the upper housing member 17 there is disposed a heater 19, having a side wall 20, which is 50 rounded outwardly in cross section. An annular depending flange 21 is secured to the heater 19, this depending flange resting against the top 15 of the lower housing member 5 which serves as a floor. There is 55 an opening 22 in the bottom of the heater 19, and through this projects a tube 23, having

a closure 24, at its upper terminal. This tube 23 projects below the bottom of the heater 19, and it is spaced from the sides of the opening 22. A depending collar 25 is 60 secured to the bottom of the heater 19, around the opening 22, this collar 25 being spaced from the tube 23, there being an annular member 26, which connects the lower terminal of the tube with the lower terminal 65 of the collar 25, to form a water chamber, around the tube 23, which is in communication with the interior of the heater 19. The collar 25 projects down in the opening 14 in the top 15, of the lower housing member 70 5, and the chimney 27 of the lamp 13 is disposed below the tube 23. There are a plurality of lateral openings 28 in the tube 23, above the bottom of the heater 19, horizontal flues 29 being secured to the tube 23 75 and having communication with the openings 28 respectively. These horizontal flues 29 are bent to form acute angles 30, the flues then extending upwardly and forming terminals 31, which project through 80 openings 32 in the top of the heater 19. There is an additional opening 33 in the top of the heater, a collar 34 being secured to the top of the heater around the said opening 33. In the top 35 of the upper housing 85 member 17, there are openings 36, which are disposed substantially above the terminals 31. The heater 19 is covered with wool or cloth 37. A door 38 is hinged to the top of the housing member 17, this door 38 being 90 adapted to close an opening in the end of the housing member 17.

In using the invention the heater 19 is filled with water, when the lamp 13 is lighted, the heat from the lamp 13 passes up 95 through the tube 23 against the closure 24. It will be seen that as the tube 23, with its head 24, has a considerable surface exposed to the water in the heater 19, the heat from the lamp 26 will be used to the best advantage. The heated air from the tube 23 passes through the flues 29, in which it tends 100 to heat the said flues, serving to raise the temperature of the water in the heater 19. As the warm air from the terminals 31 105 passes through the openings 36, it will tend to draw with it air from the housing chamber 17, which will insure a circulation of air.

Having thus described my invention, I claim as new and desire to secure by Letters 110 Patent:

1. In a chicken brooder a heater having a

- side wall curved in cross section downward and inward, a flange depending from the heater, spaced from the periphery of the heater, the flange permitting the chickens to 5 get their backs up against the side wall of the heater, while preventing the chickens from walking under the heater in such a manner as to heat their heads.
2. In a chicken brooder a housing, a 10 heater disposed in the housing and having a top with openings and a side wall converging downwardly, a supporting flange depending from the heater, spaced from the vertical plane of the periphery of the heater, 15 the flange permitting the chickens to get their backs up against the side wall of the heater while preventing the chickens from walking under the heater and thereby heating their heads, a depending annular water chamber disposed within the flange and in communication with the heater, the inner wall of said water chamber extending upwardly into the heater and having openings 20 in the upper portion thereof and a closure for its top, said water chamber depending below the horizontal plane at the bottom of the flange, and being adapted to be disposed in the housing to prevent the lateral displacement of the heater, and flues in the 25

heater connected with the openings in the 30 inner wall of the water chamber, the flues extending through the openings in the top of the heater.

3. In a chicken brooder a housing, a 35 heater disposed in the housing and having a top with openings and a side wall, a supporting flange depending from the heater, a depending annular chamber disposed within the flange and in communication with the heater, the inner wall of the said chamber 40 extending upwardly into the heater and having openings in the upper portion thereof and a closure for its top, said chamber depending below the horizontal plane at the bottom of the flange, and being adapted to 45 be disposed in the housing to prevent the lateral displacement of the heater, and tubes in the heater connected with the openings in the inner wall of the chamber, the tubes extending through the openings in the top of 50 the heater.

In testimony whereof I have signed my name to this specification in the presence of two subscribing witnesses.

WALLACE ORLANDO WITHAM.
